(57) **CLAIM**

We claim the ornamental design for a hand tool for opening beverage cans, as shown and described.

DESCRIPTION

FIG. 1 is a top perspective view of an embodiment of a hand tool for opening beverage cans according to the present invention, with handles shown in the open configuration.

FIG. 2 is a top plan view of the hand tool for opening beverage cans of FIG. 1.

FIG. 3 is a bottom view of the hand tool for opening beverage cans of FIG. 1.

FIG. 4 is a left side elevation view of the hand tool for opening beverage cans of FIG. 1.

FIG. 5 is a right side elevation view of the hand tool for opening beverage cans of FIG. 1.

FIG. 6 is a rear elevation view of the hand tool for opening beverage cans of FIG. 1.

FIG. 7 is a front elevation view of the hand tool for opening beverage cans of FIG. 1.

FIG. 8 is a bottom perspective view of the hand tool for opening beverage cans of FIG. 1.

FIG. 9 is a top perspective view of the hand tool for opening beverage cans of FIG. 1, with handles shown in the closed configuration.

FIG. 10 is a top plan view of the hand tool for opening beverage cans of FIG. 9.

FIG. 11 is a bottom view of the hand tool for opening beverage cans of FIG. 9.

FIG. 12 is a left side elevation view of the hand tool for opening beverage cans of FIG. 9.

FIG. 13 is a right side elevation view of the hand tool for opening beverage cans of FIG. 9.

FIG. 14 is a rear elevation view of the hand tool for opening beverage cans of FIG. 9.

(Continued)

FIG. 15 is a front elevation view of the hand tool for opening beverage cans of FIG. 9; and,

FIG. 16 is a bottom perspective view of the hand tool for opening beverage cans of FIG. 9.

The broken lines show portions of the hand tool for opening beverage cans which form no part of the claimed design.
